UNITED STATES PATENT OFFICE.

MAGNUS M. VOGEL AND WILLIAM J. MEYER, OF ALLEGHENY,
PENNSYLVANIA.

ELECTRIC THERMOSTAT.

No. 839,794.

Specification of Letters Patent.

Patented Dec. 25, 1906.

Application filed July 3, 1906. Serial No. 324,699.

To all whom it may concern:

Be it known that we, MAGNUS M. VOGEL and WILLIAM J. MEYER, citizens of the United States of America, residing at Allegheny, in the county of Allegheny and State of Pennsylvania, have invented certain new and useful Improvements in Electric Thermostats, of which the following is a specification, reference being had therein to the accompanying drawings.

This invention relates to electric fire-alarms or thermostats, and particularly to that class of electrical alarms in which an electric circuit is completed to sound an alarm by the expansion by heat of one of the electrodes.

The present invention aims to provide a device of the character indicated of very simple and inexpensive construction in which the parts may be quickly assembled and connected together.

The improvement consists of a base or supporting block adapted to be readily secured against a wall or like support, a strip of expandable sheet metal, means for securing the ends of the metal strip to the base, and an adjustable contact-point located adjacent to the metal strip, an alarm-bell, and electrical connections for closing a circuit through said bell when the strip expands sufficiently to contact with said adjustable contact-point.

The construction of the improvement will be fully described hereinafter in connection with the accompanying drawings, which form part of this specification, and its novel features will be defined in the appended claims.

In the drawings, Figure 1 is a front elevation of a thermostat constructed in accordance with our invention. Fig. 2 is a bottom plan view of the same; and Fig. 3 is a section, on an enlarged scale, on the line $x-x$ of Fig. 1.

The reference-numeral 1 designates a block or base, preferably made of cast-iron, although the same may be constructed of other material. An important advantage of employing a cast-iron base is that the securing-lugs for the attachment of the expandable metal strip and the adjustable contact-point may be formed integral with the block, thus simplifying the construction and reducing the cost of manufacture.

Projecting from the outer surface of the base 1 near each of its upper corners is a lug 2,

said lugs being inclined in opposite directions for the convenient attachment thereto of a strip 3 of copper, brass, or other metal which readily expands by heat. This metallic strip is bent to bow form, as shown, so that its ends will rest against the outer sides of the lugs 2, while its central bowed portion extends adjacent to the lower edge of the base 1 in close proximity to a lug 4, projecting from the base midway of its length.

The two inclined lugs 2 are provided with openings to receive suitable securing-bolts 5, provided with nuts 6 or other suitable securing means extending through corresponding holes in the ends of the strip 3. The lug 4 is also provided with an opening to receive an adjustable screw 7, the latter being preferably insulated from the lug by means of a bushing 8, of insulating material, and with an electrical conductor 9, leading from one side of a battery, the other lead 10 from the battery being connected to the one end of the metal strip 3.

A bell 11 is included in the battery-circuit, and it will be apparent from the illustration in the drawings that in case of fire the heat will expand the metal strip 3 and cause it to make electrical contact with the contact-point 7, thus completing a circuit through the bell and sounding the alarm.

By bending the metal strip to bow form the strip is brought to the most advantageous position with relation to the contact-point to insure contact by expansion, and the arrangement of the projecting lugs at opposite inclinations maintains the strip in its bowed position.

We preferably provide the block or base with openings 12 to receive nails or screws for supporting the device upon a wall, and the edges 13 of the block are beveled to impart a finished appearance thereto.

What we claim, and desire to secure by Letters Patent, is—

1. A thermostat comprising a block or base provided with oppositely-disposed inclined corner-lugs, and a central lug, a bowed strip of expandable material having its ends secured to said inclined lugs, an adjustable contact-point extending through said central lug, and an electric circuit including an alarm-bell, said contact-point constituting one terminal of the circuit and said metal

strip constituting the other terminal, and adapted to expand to contact with said contact-point to close the circuit.

2. A thermostat comprising a cast-metal block or base having integral oppositely-inclined corner-lugs, and a central lug adjacent to the lower edge of the block, a bowed strip of expansible sheet metal secured to said inclined lugs, an adjustable screw extending through said central lug, an alarm-bell, and

an electric circuit adapted to be closed by the expansion of said strip to sound an alarm.

In testimony whereof we affix our signatures in the presence of two witnesses.

MAGNUS M. VOGEL.
WILLIAM J. MEYER.
